UNITED STATES PATENT OFFICE.

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

DRAFT-RIGGING.

1,279,708.

Specification of Letters Patent. Patented Sept. 24, 1918.

Application filed July 17, 1917. Serial No. 181,095.

To all whom it may concern:

Be it known that I, WILLIAM KELSO, a citizen of the United States, residing at Pittsburgh, in the county of Allegheny and

5 State of Pennsylvania, have invented certain new and useful Improvements in Draft-Rigging; and I do hereby declare the following to be a full, clear, and exact description of the invention, such as will enable 10 others skilled in the art to which it appertains to make and use the same.

My invention relates to the construction of draft rigging for railway cars and particularly to draft rigging of a character that 15 is well adapted for application to passenger cars. The principal object of the invention is to afford simple and efficient means for pivotally connecting the coupler and draft yoke without employing the usual tail pin 20 or pivot pin, and in a manner minimizing liability of spreading or separation of the front ends of the yoke arms and the distortion or destruction of the yoke.

Generally stated, the primary object of 25 the invention is accomplished by employing a coupler with a shouldered butt adapted to be inserted between the arms of the draft yoke and to engage correspondingly curved shoulders at the forward ends of rearwardly 30 open sockets formed on the adjacent faces of the free ends of the arms of such yoke, means being provided for preventing rearward travel of the coupler independently of said yoke and for preventing spreading of the 35 free ends of the yoke, said means engaging the coupler in advance of the said shoulders and involving a plurality of members one of which extends through the coupler and horizontally overlaps the free ends of the yoke 40 arms. Other features of the invention, involving minor combinations and special constructions of elemental parts, will be hereinafter fully described and particularly claimed.

45 In the drawings chosen for the purpose of illustrating the invention, the scope whereof is pointed out in the claims,

Figure 1 is a plan view of a draft rigging embodying my invention, the cushioning 50 mechanism, which usually consists of springs and followers arranged in a well-known way within the yoke, being omitted.

Fig. 2 is a side elevation of the construction illustrated in Fig. 1, the head of the 55 coupler being omitted.

Fig. 3 is a vertical central section of the devices shown in Figs. 1 and 2, a portion of the draft yoke and the means for maintaining the coupler and yoke in assembled relation being in elevation.

60 Figs. 4 and 5 are transverse sectional views respectively taken on the lines 4—4 and 5—5, Fig. 3, looking forwardly.

Fig. 6 is a detail view showing the front of the yoke in elevation and the coupler in 65 section.

Fig. 7 is a detail view of the yoke, the forward end being in vertical central section.

Fig. 8 is a view corresponding to Fig. 3, 70 but illustrating a modified form of the invention.

Fig. 9 is a plan view of a draft rigging illustrating another form of the invention, the coupler head and the cushioning devices that are mounted within the yoke being 75 omitted.

Fig. 10 is a side elevation of the construction shown in Fig. 9.

In the form of draft rigging which is 80 illustrated in the principal figures of the drawings, 1 indicates the coupler and 2 is the draft yoke. These parts are preferably pivotally connected in such manner that the coupler is capable of swinging horizontally and also of angling vertically with respect 85

to the draft yoke. At its rear end the coupler is provided with pivotal shoulders 3 which, as shown in Fig. 3, are preferably undercut. These pivotal shoulders are adapted to engage correspondingly curved 90 and undercut shoulders 4 that are formed on the yoke 2 adjacent the coupler engaging end of the latter, said curved shoulders 4 in effect forming sockets which receive the lugs or pivot forming shoulders 3 of the coupler 95 butt. To the rear of the curved undercut faces 3, the upper and lower faces of the coupler butt are preferably tapered rearwardly, as at 5, to permit the coupler 1 to be capable of angling or swinging vertically 100 with respect to the draft yoke 2. At its coupler engaging end the yoke 2 is provided with inwardly directed lug portions 6 whose rear faces form the undercut shoulders 4 which coöperate with the pivotal lugs or 105 shoulders on the butt of the coupler. The forward or free ends of the arms of the draft yoke are stepped or shouldered, their vertically extending faces 7, 7, and 8, 8, respectively, being curved concentrically with the 110

inner pivotal bearings 4. To permit of lateral swinging or angling of the coupler 1 with respect to the yoke 2, the inner surfaces of the lug portions 6 of the yoke are formed 5 as outwardly and laterally flaring curved faces 9 which also diverge outwardly in a vertical direction to provide for vertical angling of the parts. For a short distance in advance of its butt the stem of the coupler 1 10 is curved or rounded upon its upper and lower faces, as indicated at 10. This permits the coupler to be assembled with and disassembled from the yoke 2 by rotating the coupler a quarter turn on its axis and then 15 moving it longitudinally either rearwardly or forwardly, depending upon whether the parts are being assembled or disassembled.

At a point in advance of the forward ends of the arms of the draft yoke 2 the stem of 20 the coupler 1 is formed with a vertically extending slot whose forward wall 11 is preferably inclined. This slot is adapted to receive means for preventing the forward ends of the yoke arms from spreading and thus 25 becoming disengaged from the coupler 1. The device which it is preferred to employ for maintaining the assembled relation of the yoke and coupler preferably comprises a key 12 which is provided at its ends with 30 shoulders 13 that respectively overlap the horizontal portions of the yoke between the curved faces 8 and 9 thereof. When the upper and lower faces of the coupler butt are inclined, as at 5, to permit vertical angling 35 of the coupler, a slight clearance is left between the draft yoke 2 and the shoulders 13 of the key 12 in order to allow for such vertical movement of the coupler. The key 12 may be conveniently maintained in assembled relation by means of a wedge shaped 40 key 14 that is inserted in the vertical slot of the coupler stem in advance of the key or clamp 12. The wedging member 14 is preferably provided at one end with a head or shoulder 15 having overlapping engagement with the stem of the coupler 1. It may be 45 conveniently retained in assembled position by means of a cotter 16.

The modification of the invention illustrated in Fig. 8 is substantially the same as the construction heretofore described, except that no provision is made for permitting vertical angling of the coupler with respect to the yoke. To this end the upper and lower 50 surfaces 5^a on the butt of the coupler 1^a are not beveled or tapered but are parallel, while the curved inner surfaces 9^a of the free ends of the yoke 2^a are not flared outwardly in a vertical direction. The coupler 1^a and draft 55 yoke 2^a are preferably retained in assembled position by a key 12 and wedging member 14 which are related to the coupler and the draft yoke in precisely the same way as in the form of construction already described. 60

65 Accordingly, the key and wedging member

and the parts of the coupler and yoke with which they coöperate have been indicated by reference numerals corresponding to those employed in the construction heretofore described.

In the form of construction shown in Figs. 9 and 10 the coupler 1^b is designed to be assembled with the yoke 2^b by inserting the butt of the coupler laterally between the arms of the yoke and then moving it forward 70 until the curved bearings of both members are in contact. In this construction there is no necessity for rounding the shank of the coupler in advance of its butt. The free ends of the arms of the draft yoke 2^b are formed with inwardly projecting lugs 6^b whose adjacent inner faces 9^b are parallel flat surfaces. The rear faces of these lugs form curved and preferably undercut bearing faces or sockets 4^b that are adapted to engage and coöperate with the correspondingly curved and undercut pivot lugs or shoulders 3^b on the butt of the coupler 1^b. The forward ends of the arms of the yoke are stepped, the curved vertical faces 7, 7, and 80 7, 8, respectively, having the same axis as that of the coöoperating pivotal faces 3^b and 4^b. For retaining the coupler 1^b and yoke 2^b in assembled relation and to prevent spreading or separation of the free ends of 90 the arms of the yoke, it is preferred to employ a key 12 and wedging member 14, whose relations to each other and to the coupler and draft yoke have been already described. 95

I claim:

1. In a draft rigging, the combination with a coupler, of a draft yoke connected thereto, said yoke being provided at the coupler engaging end thereof with inwardly directed lug portions, the coupler having shoulders adapted to engage the rear faces of the lug portion on the said yoke, and means for maintaining said yoke and coupler in assembled relation, said means including a member extending through the coupler in front of said yoke and adapted to engage the upper and lower faces of the said yoke. 105

2. In a draft rigging, the combination with a coupler, of a draft yoke pivotally connected thereto, said yoke being provided adjacent the coupler engaging end thereof with curved undercut pivot shoulders, the coupler having shoulders thereon coöoperating with the said shoulders of the yoke, and means for maintaining said coöoperating shoulders in assembled relation, said means including a key adapted to engage the end faces of the yoke at the coupler engaging end thereof. 115

3. In a draft rigging, the combination with a draft yoke, of a coupler pivotally connected thereto, the free ends of the arms of said yoke being curved and said yoke and coupler having coöperating shoulders curved concentric with the said curved ends of the 120 125 130

yoke, and means for maintaining the engagement of said yoke and coupler, said means including a member extending through the coupler and engaging the end faces of said 5 yoke at the coupler engaging end thereof.

4. In a draft rigging, the combination with a draft yoke, of a coupler having shouldered engagement therewith, and means extending through said coupler in advance of 10 said yoke and horizontally overlapping the free ends of the yoke for maintaining said coupler and yoke in operative engagement.

5. In a draft rigging, the combination with a draft yoke, of a coupler pivotally 15 connected thereto, coöoperating pivotal means on said yoke and coupler adapted to prevent the longitudinal separation thereof in one direction, and means movable laterally with the coupler and adjustable longitudinally thereof for engaging the said yoke 20 to prevent the longitudinal separation of said yoke and coupler in the opposite direction.

6. In a draft rigging, the combination 25 with a draft yoke provided with rearwardly open sockets on the adjacent faces of the free ends of its arms, a coupler provided with a shouldered butt, the said butt being adapted to be inserted between the arms of said yoke 30 and to engage shoulders on the yoke within the said sockets, and means for preventing rearward movement of the coupler independently of the yoke, said means engaging said coupler in advance of said shoulders 35 and comprising a member extending through the coupler and horizontally overlapping the free ends of the yoke, and means for securing said overlapping member in position.

7. In a draft rigging, the combination 40 with a coupler, of a yoke connected thereto, and means for preventing dissociation of the arms of said yoke from said coupler, said means serving to prevent the coupler from moving rearwardly independently of 45 the yoke and comprising a shouldered member extending through the coupler and a wedging member adapted to maintain said shouldered member in assembled position.

8. In a draft rigging, the combination 50 with a draft yoke, of a coupler connected thereto so as to have both lateral and vertical swinging movements with respect to

said yoke, said coupler and yoke having co-operating pivot forming shoulders, and means for preventing the disengagement of 55 the forward ends of the arms of said yoke from said coupler, said means including a wedging member and a key extending through the said coupler in advance of the yoke. 60

9. In a draft rigging, the combination with a draft yoke, of a coupler pivotally connected thereto, said yoke having at the free ends of its arms inwardly extending lug portions having curved outwardly flaring faces, the said coupler having curved faces adjacent its butt and between the adjacent faces of the lug portions of the yoke, the upper and lower curved faces of the 65 said coupler being substantially parallel, 70 whereby the coupler may angle vertically with respect to the said yoke.

10. In a draft rigging, the combination with a draft yoke, of a coupler pivotally connected thereto, said yoke being provided 75 at its forward end with inwardly extending lug portions the inner and outer vertical faces of which are concentrically curved, a coupler having a shouldered butt the shoulders of which are adapted to engage the 80 inner shoulders of the yoke lugs, the adjacent faces of the yoke lugs and the upper and lower faces of the coupler butt being rearwardly tapered, to thereby permit vertical angling of the coupler and yoke, and 85 shouldered means movable by the coupler with respect to the said yoke for maintaining said yoke and coupler in engagement.

11. In a draft rigging, the combination with a draft yoke having spaced arms the 90 forward ends of which are provided with inwardly extending lugs, said lugs having their adjacent faces inclined to the longitudinal axis of the said yoke, a coupler provided with a shouldered butt, the said 95 shoulders being adapted to engage the said lugs on the yoke, the upper and lower faces of the said butt being inclined to correspond to the inclination of the adjacent faces of the said yoke lugs, whereby the said coupler 100 may angle vertically with respect to the said yoke.

In testimony whereof I affix my signature.
WILLIAM KELSO.
